UNITED STATES PATENT OFFICE.

ARTHUR T. WOODS, OF CHAMPAIGN, ILLINOIS.

NUT-LOCK.

SPECIFICATION forming part of Letters Patent No. 313,149, dated March 3, 1885.

Application filed June 14, 1884. (No model.)

To all whom it may concern:

Be it known that I, ARTHUR T. WOODS, a citizen of the United States, residing at Champaign, in the county of Champaign and State of Illinois, have invented certain new and useful Improvements in Nut-Locks; and I do hereby declare the following to be a full, clear, and exact description of the invention, such as will enable others skilled in the art to which it appertains to make and use the same.

My invention relates to improvements in nut-locks used in connection with bolts and nuts which are applied for the retention of fish-plates on railway-rails.

15 The object of my invention is to provide a strong and durable and at the same time inexpensive device, which, when properly adjusted, will securely lock and hold the nut to which it is applied in position upon the bolt. 20 It is of such form of construction as to be free from danger of breaking by sudden strains or severe shocks, and may be readily removed or readjusted without injury to its structure. The manner in which this object is attained 25 is hereinafter fully described, reference being had to the accompanying drawings and letters of reference marked thereon, which constitute a part of this specification.

Similar letters refer to similar parts throughout the several views.

In the accompanying drawings, Figure 1 is a section on line xx of Fig. 2. Fig. 2 is a side view of washer and nut-lock as applied to joint of rail, with straight fish-plate and square nut. Fig. 3 is a plan of Fig. 2, the parts being shown as removed from the rail. Fig. 4 is a side view of the device, in which the locking-plate is shown as provided with a notch suitable for hexagonal nuts. Fig. 5 is a side view upon one-half the scale of Fig. 2, the locking-plate being turned upward, so as to clear the nut, this being its position when the nut is being adjusted.

Referring to the drawings, a represents a washer, made of iron or other suitable material, bent at a point intermediate of its ends, so as to form two right angles to the bent middle portion thereof, a hole being punched at a point near one of its ends to accommodate 50 the bolt b , and the hole h provided for the re-

ception of the locking-plate c . The hole h may be either round, square, or of any other desired shape, depending upon the form of that portion of the locking-plate which is to pass through it. The rear end of the locking-plate c is bent at right angles to its forward end, forming the neck J , and is again bent at right angles to the neck, in a direction away from its forward end, so as to enable the bent portion to pass through the hole h in the washer. The opposite end of the locking-plate is provided with a notch, $l m$, of such form as to be adapted to the shape of the nut used. The length of the locking-plate is such that when in the locking position shown in Fig. 2 the neck J will bear against the edge of the hole h which is farthest removed from the bolt b , while its opposite end will be supported upon the nut by the lip m , the face l being in contact with one of the edges of the nut, or nearly so, the nut being thus prevented from turning, while the corner k of the locking-plate bears against the fish-plate and prevents its removal without first slackening the nut, though, when desired, it may be turned in the hole h , so as to clear the nut and occupy the position shown in Fig. 5. When detached from the bolt, the locking-plate c and the washer a are entirely separate.

I do not wish to confine myself to any particular form of locking-plate, as it is evident that the notch in the same may be varied so as to conform to the style of nut used.

Having thus described my invention, what I claim as new, and desire to secure by Letters Patent, is—

In a nut-lock, the combination of the locking-plate c , having the neck J , and bent at right angles to the neck in a direction away from its forward end, with the washer a , bent as shown, and having a hole near one of its ends for the accommodation of the bolt b , and the hole h , for the reception of the locking-plate, substantially as and for the purpose set forth.

In testimony whereof I affix my signature in presence of two witnesses.

ARTHUR T. WOODS.
